FIG. 1

FIG. 3

FIG. 2

FIG. 4

FIG. 5

FIG. 6

FIG. 1 is a perspective view of a chord-producing finger bar for a stringed musical instrument or similar article, showing my new design with the finger-holding elastic in position of use;

FIG. 2 is a top plan view with the finger-holding elastic retracted;

FIG. 3 is an end elevational view as viewed from the left in FIG. 2;

FIG. 4 is an opposite end elevational view as viewed from the right in FIG. 2;

FIG. 5 is a side elevational view as viewed from the bottom in FIG. 2; and

FIG. 6 is an opposite side elevational view as viewed from the top in FIG. 2.

The broken line showing of a player's finger in FIG. 1 is for illustrative purposes only.

I claim:

The ornamental design for a chord-producing finger bar for a stringed musical instrument or similar article, as shown and described.
